UNITED STATES PATENT OFFICE.

HUGH WILLIAMSON KELLY, OF PROVIDENCE, RHODE ISLAND, ASSIGNOR OF ONE-HALF
TO AUBREY LOVE, OF RIDGEWOOD, NEW JERSEY.

PROCESS OF MAKING TRACK-TORPEDOES.

1,304,487.

Specification of Letters Patent.

Patented May 20, 1919.

Application filed December 3, 1917. Serial No. 205,184.

To all whom it may concern:

Be it known that I, HUGH WILLIAMSON KELLY, a citizen of the United States, and a resident of Providence, Rhode Island, have invented Improved Processes of Making Track-Torpedoes, of which the following is a specification.

My invention relates to track torpedoes of the type set forth in my Patent Number 1,248,670, dated December 4, 1917, and the object of my present invention is to form a molded torpedo of rubber or rubber-containing material with the explosive charge positioned within the same; said torpedo, or the molded shell comprising the same, having integral lugs for gripping the head of a rail in order that it may be properly positioned with respect to said rail.

According to my present invention, the detonating or explosive material, whether contained within a suitable envelop or not, as may be necessary or desirable, is introduced into a suitable mold with the desired amount of rubber or rubber-containing material properly positioned with respect to the same, and then the mold with the contained material is subjected to heat and pressure so as to produce an integral continuous-walled container or shell having the integral lugs whereby it may be secured to the head of a rail, and inclosing such detonating charge.

These and other features of my invention are more fully described hereinafter, reference being had to the accompanying drawings, in which:

Figure 1, represents one form of molded torpedo of the type to which my invention relates positioned upon a rail head.

Fig. 2, is a longitudinal sectional view of the same.

Fig. 3, is a perspective view of the finished torpedo.

Fig. 4, is a longitudinal sectional view of a mold with a detonating charge positioned within the same; showing the space to receive the rubber or rubber-containing or analogous material to inclose the same.

Fig. 5, is a cross sectional view on the line V—V. Fig. 4.

Figs. 6 and 7, are views illustrating modified forms of molded torpedoes within the scope of my invention.

Figs. 8 and 9, are sectional views, similar

to Fig. 4, showing forms of molds in which 55 torpedoes of the shape or type illustrated in Figs. 6 and 7, may be formed.

Figs. 10 and 11, are cross sectional views similar to Fig. 5, of the molds shown in Figs. 8 and 9, and

Figs. 12, 13, 14, 15, 16 and 17, illustrate other modifications within the scope of my invention.

The shell 1 of the torpedo illustrated in Figs. 1 and 2, *et seq.*, may be a thin-walled 65 structure, with the ends beveled as at 2, and the sides beveled as indicated at 3; the base 4 being shaped to conform to the surface of the rail-head, with rail-engaging lugs 5 continuous with the walls of the 70 structure.

In forming or making this structure, the charge is disposed within the mold in which the shell is shaped, as shown in Fig. 4, in which the charge 6 is represented as inclosed within a suitable envelop 7, and the rubber or other material to form the shell of the structure is placed within such mold in the space indicated at 8. In some instances the envelop 7 may be omitted. The 75 mold with its inclosures thus prepared is then subjected to the necessary heat and pressure whereby a continuous-walled shell inclosing the charge and having the rail-engaging lugs 5 is formed as a single integral and homogeneous structure, as illustrated in the several views of the drawing. If desired, the charge may be premolded or shaped in the form of a cake or block, and in such instance the envelop or container 7 80 90 may be omitted.

In the form of torpedo shown in Fig. 6, a broad detonating-charge—container 1^a is shown; the charge may be circular in shape with convex surfaces 2^a, and the lower portion will have the usual rail-engaging lugs 5. Figs. 8 and 10 show clearly the manner in which this form of torpedo is made; the detonating charge being either a premolded block, or contained within a suitable envelop, and being inserted in the mold around which the sections of rubber or rubber-containing material are placed.

In the form of torpedo shown in Fig. 7, a rounded central chamber 1^b is provided for 105 the detonating charge; said chamber surrounding the strip or band forming the base 4^b, and the ends of said base are pref-

- erably stiffened by integral bracing members 9. Figs. 9 and 11, show the manner in which this form of torpedo is made and, as in the other structures referred to, the 5 detonating charge may be either a pre-molded block, or contained within a suitable envelop before insertion in the mold.
- It will be understood that the torpedoes 10 may be of substantially the shape and character illustrated in the several perspective views; they are provided in each instance with an arched base portion 4, 4^a or 4^b, respectively, substantially conforming to the surface of the rail, and they are provided 15 with integral rail-engaging lugs 5 which may have their inner faces roughened by corrugations 10, or provided with other means to assist in retaining the same upon the head of a rail.
- 20 In some instance it may be desirable to provide the torpedoes with straps 5^a, long enough to extend under the head of the rail, and in Fig. 12, I have shown a sectional view of a torpedo of this type. Such 25 form of torpedo may be molded in a mold of the character illustrated generally in Figs. 4 and 5; provision being made for the formation of the elongated straps with their ends to underlie the rail heads, and in 30 Fig. 13, I have shown a mold of this type.
- It will be understood, of course, that 35 forms of these molded torpedoes may be, if desired, made in more than one piece, and in Fig. 14, I have shown a type of a two-part structure in which the parts 11 and 12, are 40 separately molded and the whole then assembled after the detonating material has been set in place. In this form of the torpedo, the member 11 will have rail-engaging 45 lugs 5^b of substantially the same type as those illustrated in Figs. 1, 2 and 3; the same being integrally connected with said member 11 which has lugs or ears 13 whereby it may engage the walls of the charge-containing 50 section 12. This section may also be molded, and the same will be hollow to receive the charge 6 of detonating material which will be confined in place upon application to the lug-carrying base. If desired, 55 a cementing body of some nature may be employed to connect the parts together or to hermetically seal them and thereby protect the detonating material from the ingress of dampness or moisture.
- 55 In Fig. 16, I have shown a sectional view of another form of torpedo which may comprise a tubular member of compressible material. In this form of structure, I may provide a tubular device 15 of rubber, or of 60 any suitable friction fabric having a water-proof wall, and when finished, its ends will be open for the reception of independent lugs 16, which may be previously molded and which may be attached to the ends of said 65 tubular member in any suitable manner.

For instance, said lugs may be sewed to the ends of the tubular member as indicated at 17.

In referring to the shell of the torpedo as made of rubber, it will be understood, of course, that what is meant is a rubber-containing material, the quantity of rubber in which may be relatively small. The object is to provide a relatively flexible structure suitable for the purpose and one that will be non-flying and therefore not dangerous by reason of any flying parts under the detonation of the charge. 75

The connection between the lugs and the base of the shell or container in all forms of my improved structure are preferably of a relatively better grade of material than that comprising the container, so as to insure the desired resiliency and at the same time the required tension upon the lugs 5 when 80 they are placed in a rail-engaging position.

As this application possesses matter in common with an application filed by me May 27, 1916, Serial Number 100,259, it is to be treated as a continuation of said prior 90 application as far as the common subject-matter is concerned.

I claim:

1. The process of making track torpedoes, which comprises the preparation of a charge 95 of detonating material, placing the same within a mass of rubber or rubber-containing material so disposed as to wholly inclose such detonating charge, and finally applying heat and pressure to shape the rubber or 100 rubber-containing material into a homogeneous shell of the desired form and simultaneously inclose the charge of detonating material.

2. The process of making track torpedoes, 105 which comprises the preparation of a charge of detonating material, placing the same within a mold with a mass of rubber or rubber-containing material so disposed in the mold as to wholly inclose such detonating 110 charge, and finally applying heat and pressure to the mold to shape the rubber or rubber-containing material into a homogeneous shell of the desired form and simultaneously inclose the charge of detonating material. 115

3. The process of making track torpedoes, which comprises the preparation of a charge of detonating material, inclosing the same in a suitable casing or envelop, placing such incased charge within a mass of rubber or 120 rubber-containing material inclosing the same, and finally applying heat and pressure to shape the rubber or rubber-containing material into a single integral and homogeneous shell and simultaneously inclose the detonating charge. 125

4. The process of making track torpedoes, which comprises the preparation of a charge of detonating material, inclosing the same in a suitable casing or envelop, placing such 130

incased charge within a mold with a mass of rubber or rubber-containing material inclosing the same, and finally applying heat and pressure to the mold to shape the rubber or rubber-containing material into a single integral and homogeneous shell and simultaneously inclosed the detonating charge.

5. The process of making track torpedoes, which comprises placing a charge of detonating material within a mass of rubber or rubber-containing material wholly inclosing such detonating charge, and finally applying heat and pressure to shape the rubber or rubber-containing material into a homogeneous shell inclosing the charge of detonating material.

6. The process of making track torpedoes, which comprises placing a charge of detonating material in a mold within a mass of rubber or rubber-containing material wholly inclosing such detonating charge, and finally applying heat and pressure to the mold to shape the rubber or rubber-containing material into a homogeneous shell inclosing the charge of detonating material.

7. The process of making track torpedoes, which comprises placing an incased charge of detonating material within a mass of rubber or rubber-containing material wholly inclosing such detonating charge, and

finally applying heat and pressure to shape the rubber or rubber-containing material into a homogeneous shell inclosing the incased charge of detonating material.

8. The process of making track torpedoes, which comprises placing an incased charge of detonating material in a mold within a mass of rubber or rubber-containing material wholly inclosing such detonating charge, and finally applying heat and pressure to shape the rubber or rubber-containing material into a homogeneous shell inclosing the incased charge of detonating material.

9. The process of making track torpedoes, which comprises molding separate members of rubber or rubber-containing material with interlocking or engaging portions, fitting a charge of detonating material within one of said members, locking the members together to inclose the detonating material, and sealing the joint between said members.

10. The process of making track torpedoes, which comprises molding separate members of rubber or rubber-containing material, fitting a charge of detonating material within one of said members, and finally connecting said members together in a homogeneous shell completely inclosing the detonating material.

HUGH WILLIAMSON KELLY.
